UNITED STATES PATENT OFFICE

2,421,225

REUSABLE NESTING SHIPPING CONTAINER

William L. Stensgaard, Chicago, Ill., assignor to
 W. L. Stensgaard and Associates, Inc., a cor-
 poration of Illinois

Application October 6, 1943, Serial No. 505,099

2 Claims. (Cl. 229—23)

1

This invention relates to a container, and more particularly to a reusable shipping container.

One feature of this invention is that it provides an improved container or carton; another feature of this invention is that the main body of the container may be used again and again; still another feature of this invention is that a complete container, as for example of cubical shape, is formed of only two principal portions and means for holding these portions in desired relationship; yet another feature of this invention is that the principal portions of which the container is formed are so shaped that large numbers of such portions may be nested in a relatively small space for return to the original point of shipment; a further feature of this invention is that the container walls may be readily made of double thickness where desired; and other features of this invention will be apparent from the following specification and the drawings, in which:

Figure 1 is a perspective view of two U-shaped members adapted to be intermeshed to provide a generally cubical container; Figure 2 is a perspective view of a completed container embodying this invention, with a portion of the adhesive tape broken away better to show a way in which the cord or other flexible tying element is passed through openings in the edge of the U-shaped members; Figure 3 is a view of the U-shaped members of two containers nested for return to the original shipping point; and Figure 4 is a cross sectional view of a container made of four U-shaped members so that each wall is of double thickness.

Crates, cartons, chests, and a number of other containers are used for the shipment of goods, but all of these present certain problems in economical re-use of the principal parts of the container. I have devised an improved reusable shipping container which consists of two principal substantially rigid U-shaped members adapted to be intermeshed with their planes at right angles to provide the container and adapted to be nested for return to the original shipping point. The finished container is very rugged and meets all shipping requirements; yet it may be easily put together and taken apart, and the only things which need to be renewed are the tying cords and paper tape.

In the particular embodiment of this invention illustrated in Figure 1 there are a pair of substantially rigid U-shaped members 10 and 11. These are made of or formed from substantially rigid sheet material, as plywood, Masonite, or the

2

like. The sheet from which the U-shaped member is formed would, in the case of a cubical container, have a length three times its width; and it would be steam-formed or otherwise shaped to the desired U-shape illustrated, so that the resultant U-shaped member would be substantially rigid and would remain in that form. The sheet material would normally be from $\frac{1}{8}$ to $\frac{3}{8}$ of an inch thick, depending upon the size of the desired finished container, which might be a relatively small cube or a cubical or other rectangular container of dimensions running up to several feet.

As may be best seen in Figure 1, the plane of the member 10 (speaking with respect to the plane in which it presents a U-shaped appearance) is at right angles to that of the member 11, so that when they are moved together they intermesh or cooperate to provide the six walls of the cubical container illustrated in Figure 2. The edges of the various walls which lie adjacent the edges of the walls of the other member are provided with openings, as the openings here identified as 10a—10f, etc. These holes may be about $\frac{1}{2}$ inch from the edge, for example, and so arranged that they lie adjacent each other when the members are intermeshed as the holes 10a and 11a shown in Figure 2. After the members have been assembled around the goods to be shipped in the container, they are held together in cooperative relation in any desired manner. In the embodiment shown, cords 12 are laced through the cooperating holes to firmly hold the members together; and then a flexible adhesive tape, as the paper tape 13, is placed around all of the adjacent edges to completely seal the container and prevent any possibility of loss of its contents.

When the container has reached the delivery point, it is only necessary to cut the tape and cord to separate the two members, whereupon the merchandise is readily accessible. After the merchandise and any packing therearound has been removed the members may be nested as in Figure 3, where the members 10 and 11 and two other similar members are nested for return to the original shipping point. It will be understood that a large number of these members may be piled on each other in a relatively small space with only such distortion of their shape as is within the elastic limits of the plywood or similar substantially rigid material of which the members are made.

Where the merchandise is particularly fragile, an even stronger container can be made by first

making a container as shown in Figure 2, and then intermeshing two other members around the outside of the container shown in Figure 2, with the planes of these latter members different from that of the members making the inside container. The result is a container of the type shown in cross section in Figure 4, where further U-shaped members 14 and 15 are intermeshed around the inner members 10 and 11. Where such a double thickness container is desired it is preferable to have one set of members formed into a slightly larger U-shape than the others; although the members generally have enough "give" that such a container can be formed of the same size members if they are forced into position.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. A reusable merchandise container of approximately cubical shape, formed of only two principal parts which for return after reuse may be nested together along with other similar parts, comprising: a pair of substantially rigid U-shaped members of sheet material such as plywood, Masonite, and the like, each of said members before being formed into U-shape having a length several times its width and each after being formed into U-shape having an end section and a pair of substantially parallel wing sections integrally connected to the end section, said sections being substantially rigid with only a slight flexibility at their connecting joints, each of said wings along their three exposed edges being free of any lateral projections and separable from the corre-

sponding edges of the mating member to enable reuse, said members in use being intermeshed with the side sections of one member occupying planes at right angles to the planes of the side sections of the other member; the edges of the wing sections having apertures for receiving securing cords; cords passed through said apertures and extended around the container and tied with the cords extending substantially medially of each side of each member; and flexible adhesive tape overlying and secured to the adjacent edges of the sections.

2. A shipping container as claimed in claim 1, including an additional pair of similar members adapted to surround the first pair; and means for releasably maintaining said additional members in intermeshed relationship.

WILLIAM L. STENSGAARD.
